FARE REGISTER

Soren Madsen, Bergenfield, N. J., assignor of one-fourth to Joseph F. O'Brien, Englewood, N. J.

Application October 19, 1935, Serial No. 45,734

5 Claims. (Cl. 235—32)

This invention relates to improvements in fare registers.

One of the objects of this invention is to produce a mechanically-actuated fare register, and particularly a fare register of the portable type, which will be capable of accurately registering the values of coins the larger of which has the smaller value, on a single conventional counter, which is adapted on a relatively short shaft movement to count "one" and on a relatively longer shaft movement to count "two", and thus to cause the coin of larger diameter to produce the shorter movement and vice versa.

Still another object of my invention is to provide, in a device of the character specified, mechanism whereby insertion of a nickel will register upon a single counter as "one"; the insertion of a dime will register on said counter as "two", and which will permit insertion and passage therethrough of a cent without any registration whatsoever.

Another object of my invention is to provide a pair of levers comprising a primary counter-moving lever and a compensating lever located at opposite ends of a coin slot and latches controlling said levers whereby a coin of small diameter will be capable of actuating only one of said levers to produce a relatively long movement on the counter and to make a count of two, while a coin of larger diameter will be compelled first to actuate the compensating lever and thereafter to cause a short movement of the primary lever to produce a count of one.

Another object of my invention is to arrange a primary latch and a secondary latch relative to the said compensating lever in such manner that the coin of small diameter, (the dime) will be incapable of simultaneously unlatching both of said latches and such latches will preferably be so arranged that the secondary latch will be incapable of operation except through simultaneous movement of the primary latch for the compensating lever and of the primary counter-moving lever, which simultaneous movements cannot be accomplished by a dime, but can be made with a nickel.

Another object of my invention is to provide, in a device of the character specified, a pair of spring-pressed downwardly-inclined face-gripping members adapted upon insertion to contact with the face of the inserted coin and upon an attempt at retraction or movement in the opposite direction to grip and bite into the coin so

as to effectively prevent withdrawal thereof from the slot.

Another object of my invention is to provide a construction of fare box embodying a casing provided with a counter, having mechanism arranged to be moved to count one by a relatively short shaft movement and to be moved to count two by a double shaft movement, in combination with a counter-actuating mechanism engageable with the edges of a coin at opposite sides thereof, said mechanism being so arranged that a small coin will cause a greater movement of the counter-actuating shaft to produce a double count on the counter and a coin of larger diameter will produce a lesser movement of the counter shaft to produce a movement adapted for a single registration on said counter mechanism.

Still another object of my invention is to provide a fare register construction that will not only count or indicate nickels as "one" and dimes as "two", but which will permit pennies to pass through the slot of the fare box without registration or counting.

In general terms, my invention comprises a fare-register construction embodying a counter mechanism arranged upon a short shaft movement to register, count, or indicate an increase of "one", and upon a greater shaft movement to register, count or indicate an increase of "two", in combination with lever mechanism actuated by engagement of the opposite edges of coins for causing a coin with a larger diameter to produce a relatively short movement of said register shaft and a coin with a shorter diameter to produce a relatively greater movement of said shaft, said coin-actuated mechanism comprising a casing having a coin-slot obstructed at one end by a main pivoted counter-actuating lever yieldingly pressed into slot-obstructing position by a relatively strong spring and having a connection with said registering mechanism, said slot being obstructed at the other end by an auxiliary doubly latched-lever yieldingly pressed into slot-obstructing position by a relatively weak spring, said levers being thus spaced from each other to permit insertion of a coin between the same and to be engaged by the opposite edges thereof. Said auxiliary lever is provided with a latch member for latching it in coin-obstructing position and with a coin-engaging projection, said parts being so arranged at different levels and distances from the main lever that a dime or coin of smaller diameter cannot simultaneously unlatch the latch of the auxiliary lever and move the

main lever but can and will simultaneously engage at one side edge with the coin-engaging projection of the unlatched auxiliary lever (while said lever is in stationary position at one side edge) and at the other side edge with the main counter-actuating lever, thus causing a long swing, movement or throw of said main counter-actuating lever and producing on said counter mechanism a long shaft movement and a count of two. A nickel, or coin of larger diameter on the other hand will simultaneously engage at opposite edge with the main lever and said latch and will first unlatch said weaker auxiliary lever to cause an initial limited movement of predetermined extent in a direction opposite to the counter-actuating movement of the main lever and thereafter said nickel in its further downward movement because of said predetermined initial movement in the direction opposite to the counter-actuating movement will cause only a relatively short swing, throw or movement of the stronger spring-pressed counter-actuating lever and thus will produce on said counter-mechanism only a short shaft movement and a count of one.

My invention also comprises the positioning of the parts and the limiting of the initial movement of said auxiliary lever to such an extent that a coin having a diameter intermediate the nickel and dime such as the penny will in its movement through the slot unlatch the relatively weakly spring-pressed auxiliary lever to permit the same to have said initial movement but will not move the said lever to its full limit of movement and consequently will not produce any counter-actuating movement of the counter-actuating lever, and no counting movement of the shaft of the counter will occur.

The preferred construction of my invention also embodies means for simultaneously engaging the opposite faces of a coin inserted in the coin slot to prevent withdrawal after any partial insertion thereof.

With these and other objects in view the invention comprises the combination of members and arrangement of parts so combined as to coact and cooperate with each other in the performance of the functions and accomplishment of the results herein contemplated, and comprises in one of its adaptations the species or preferred form illustrated in the accompanying drawings, in which:

Fig. 1 is an elevation of the rear side of my fare box with a part of the casing removed;

Fig. 2 is a view from the front side partly in elevation and partly in section of a unit of the mechanism shown in Fig. 1 removed from the casing;

Fig. 18 is a view similar to Fig. 11 showing the position of the parts when a dime is being counted.

Referring now to Figs. 1 to 6 of these drawings which illustrate a preferred embodiment of my invention, 1 indicates a fare register casing having at its upper end a plate 2' provided with a coin slot 2 and having coin-actuated lever mechanism mounted therein preferably between two plates of a frame 3, supported in the casing by pins 4, 4', and comprising front and rear plates 3', 3'a suitably spaced and fastened together to provide a coin-channel therebetween which registers with the coin slot 2 in the upper plate 2' of the casing 1. As illustrated, I pivotally mount between the plates 3', 3'a a spring-pressed counter-operating lever 5 which, as shown, is pivoted at 5c and has a short arm 5' extending upwardly to obstruct one end of the coin-slot 2 and a long arm 5a extending downwardly and pivotally connected through a slot 3b in the frame plate 3'a to a counter-actuating slide 6 movable to slide on the outer surface of said frame plate and guided thereon by a pin-and-slot connection 6', 6'a, said slide being operatively connected with a rotatable shaft 7 of a counter-mechanism 8 by means of a rod 9 which is fastened at one end by the pin 9' to the slide 6 and at the other end is pivoted at 10 to a crank arm 11 fastened on said shaft 7.

Obviously, movement of the lever 5 about its pivot 5c will cause a sliding movement of the slide 6 and a turning or revolving movement of the shaft 7 to actuate the counter-mechanism 8. This counter mechanism 8, which is conventional and does not per se constitute any part of my invention, has single and double movements and is so arranged that by a single or short predetermined movement of the shaft 7 the counter 8 will indicate a change of one number while a longer movement, of double extent, of said shaft will cause said counter to indicate an increase of two numerals or digits. Obviously, therefore, a movement of the slide 6 by the lever 5 for a predetermined short distance will produce a movement of said counter shaft to indicate "one" and a greater movement of said slide 6 by the lever 5 will cause an indication of two numerals or digits on said counter.

In accordance with my invention the counter-actuating lever 5 will be moved a greater distance by a coin of shorter diameter than by a coin of greater diameter, thus enabling me to utilize a nickel of relatively greater diameter to

count "one" and a dime of relatively shorter diameter to count "two" on said counter.

In the preferred embodiment of my invention, the lever 5 is spring-pressed into normal slot-obstructing position and is arranged to multiply at its lower end movement of the upper end thereof.

In said preferred embodiment of my invention, the lever 5 is provided with a toe or nose 5^b which is situated slightly below the slotted plate 2' and partially obstructs at said end the entrance of a coin through said slot 2 and I provide mechanism at the other end of the coin slot adapted to gauge coins inserted and upon the insertion of a nickel to produce a relatively short movement of the lever arm 5' and upon the insertion of a dime to produce a relatively longer movement of said lever arm 5^b. This is accomplished by using a space-freeing lever, a predetermined movement of which in the opposite direction will compensate for the difference in diameter of a nickel over the short movement of the counter-actuating lever 5' which is required to produce said count of one. For this purpose, I pivotally mount beneath the opposite end of the coin slot 2 an auxiliary lever 12, movable to free space and compensate as aforesaid, and which as shown, is pivoted between the plates 3' and 3^a on the pivot 12'. Said lever 12 is provided at its upper end with a coin engag- 30 ing toe 12^a disposed beneath the coin slot and obstructing, at the end of the slot opposite to the toe 5^b, the entrance of coins therethrough. This lever 12 is latched by a primary spring-pressed latch member 13 releasable only through movement of the counter-actuating lever 5 and is also provided with a secondary spring pressed latch 13' having a latching-toe 13^a also disposed beneath the coin slot so as to partially obstruct 40 the same and preferably disposed above and to one side of the toe 12^a of the said lever 12 and more remote from the opposite toe 5^b. The latch-toe 13^a is as shown latched to a plate 13^b directly beneath the coin slot plate 1'. The latch member 13 is pressed into normal latching position by a spring 13^c and the latch member 13' is pressed into normal latching position by the spring 13^d.

This arrangement of the lever 12 and latches is such that when a dime or coin of small diameter is inserted through the coin slot 2 it cannot simultaneously unlatch the secondary latch member 13' of the auxiliary member 12 and at the same time engage the main lever 5 to move 55 the same and release the latch 13.

The main lever 5 is yieldingly pressed into slot-obstructing position by a relatively strong spring 14 while the auxiliary lever 12 is pressed into slot-obstructing position by a relatively weak spring 15. When a dime is so inserted, the double-latched lever 12 will thus remain latched and the dime will abut and engage at one edge against the fixed toe 12^a of the lever 12 so that further pressing in of the dime will cause a relatively large movement to the right as shown in Fig. 3 of the lever arm 5' of the lever 5, thus causing a relatively long movement of the slide and a movement of double extent of the shaft 7 of the counter 8 to cause a count of "two" to be indicated on said counter.

When, however, a nickel of large diameter, is inserted in said slot 2 it will have a diameter sufficiently large to simultaneously engage the nose 5^b of the lever 5 and the latch toe 13^a of the spring-pressed latch 13', and this engage-

ment will release the primary latch of the lever 12, thus allowing the lever 12 to be swung to the left as shown in Fig. 4, until it reaches its limit of movement, which movement, as shown, is limited by a stop 15^a, whereupon the nickel being 5 of insufficient diameter to move the lever 12 further to the left will thereafter act further upon the lever 5 but will produce on said lever only a short movement which will cause the slide and shaft 7 to be similarly moved a short distance 10 so as to produce a count of "one" only, on the counted mechanism.

In the preferred embodiment of my invention, the parts are so positioned that a coin having a size intermediate the size of a dime and a nickel 15 will have sufficient circumference to simultaneously engage the nose 5^b of the lever 5 and the latch to unlatch the lever 12 but will be of sufficient diameter only to move this lever 12 to its full limit of movement without excess and 20 consequently will be permitted to pass through the coin-slot without moving the counter-actuating lever 5 to produce a counting movement of the slide 6 and shaft of the counter-mechanism, and thus passing through the device without being 25 registered.

In accordance with the preferred form of my invention, I provide spring-pressed pivoted wedge levers 16, 17 for engaging the opposite faces of the coin upon insertion thereof and thus preventing withdrawal of the coin after partial insertion in the coin slot.

In said preferred embodiment illustrated, the lever 16 is pivoted on pin 16' in bearings 16^a on the frame plate 3' while the lever 17 is pivoted on pins 17' in the bearings 17^a on the frame plate 3^a. These levers have toes extending toward each other and inclined downward from their pivots to obstruct the coin slot from opposite sides thereof. The opposite ends 16^b, 17^b 40 are preferably adapted to have a given degree of free movement to permit the insertion of a coin within the slot. After such predetermined amount of free movement, however, the lever arm 16^b is engaged by a spring-actuated contact arm 18' of a crank member 18 mounted in bearings 18^a and being turned in the said bearings by actuation of a short crank arm 18^b. The contact arm 18' of the lever 18 is swung into engagement with the lever 16^b by pressure of the spring 20 which is stretched and strengthened 45 upon an actuating movement of the lever 5 and the slide 6. The lever 17 is similarly controlled by a crank member 19 having a contact arm 19' and similarly mounted in bearings 19^b and 50 provided at its opposite ends with a short crank arm 19^b which is resiliently pressed into initial position by the spring 20 but is forced further into engaging position by an actuating movement of the said lever 5 and slide 6. 55

A conventional bell 21 illustrated in dotted lines in Fig. 1 is preferably provided together with means for ringing the same. As shown the bell is mounted on an arm 22 secured to a bracket 22' and a bell ringing hammer 23^a is mounted at 65 one end of a bell-ringing lever 23 pivoted intermediate its ends at 23' on one end of the pin 6' and the opposite end 23^b of said lever 23 is connected by link 23^c to pin 23^d fixed on the primary lever 5 and which is movable in an arcuate slot 23^e in the wall 3' of the frame 3 to cause a bell-ringing movement of the lever 23 upon the actuation of the lever 5 by the insertion of a coin.

In operation, it being understood that the lever 5 has a range of movement sufficient to produce 75

plural registering movements of the counter-actuating shaft, when a dime or coin of relatively short diameter is inserted through the coin slot as illustrated in Fig. 3, the diameter of the coin will be too short to simultaneously engage and release the latch 13^a of the lever 12 while engaging the nose 5^b of the lever 5 . The nose 12^a of the lever 12 will therefore be held stationary and retained in a position projecting beneath the left-hand end of the coin slot and when such a small coin or dime is forced downwardly it will, as shown in Fig. 3, engage at one edge against the nose of the lever 12 in stationary position and its opposite edge will press the nose 5^b of the lever 5 laterally to the right. This movement of the nose of the lever 5^b will be sufficient to produce, through the train of mechanism, which is connected to the opposite end of said lever 5 as hereinabove described, a double or plural registering movement. During this double registering movement, the primary latch 13 will be raised and released by engagement of the slide 6 with its opposite end, but as the lever 12 is also latched by the secondary spring-pressed latch $13'$, the release of the latch 13 will not release the lever 12 which is, as above indicated, held in stationary position. The dime therefore, because of its short diameter, acts only to move the lever 5 a long or plural registering movement.

When a coin of relatively long diameter, such as a nickel, as shown in Fig. 4, is inserted into the coin slot, the longer diameter thereof will be sufficient to cause its opposite edges to engage the nose 5^b of the lever 5 simultaneously with the latching toe 13^a of the secondary spring-pressed latch $13'$. Insertion of the nickel, therefore, will first release the latch 13 . It will then engage the toe 5^b of the lever 5 and force it outwardly to release the primary spring-pressed latch member 13 from engagement with the lever 12 , whereupon the lever 12 being urged by less spring pressure than lever 5 will move to the left as shown in Fig. 4, thus freeing the path of the nickel and permitting the movement of the nickel downwardly to the coin chute. Obviously, because of this compensatory movement of the lever 12 , the lever 5 will only be caused to move a short predetermined distance which however, will be sufficient to produce on the actuating shaft of the counter through the transmission means hereinabove specified, a single registering movement.

When a coin of intermediate diameter, such as a penny, is inserted, the lever parts are preferably positioned so that the penny will simultaneously engage the nose 5^b of the lever and the latching toe 13^a of the spring-pressed latch $13'$. The diameter of the penny, however, is such the edges thereof will only, in accordance with the illustrations shown in Fig. 5, press the nose 5^b of the lever 5 a very short distance to the right, and this movement of the lever 5 will be insufficient to produce a registering movement on the actuating shaft of the counter, though it will be sufficient to raise the primary latch 13 in order to release the lever 12 to enable movement of the same so as to free the path of the penny without a registering movement of the lever 5 .

In the form of my invention illustrated in Figs. 1 to 6, I preferably provide means for successively displaying each of the coins registered, and for this purpose each of the coins after dropping through the frame 3 passes down through a coin chute 24 into a compartment 25 (Figs. 1

and 6) having a movable-bottom 26 movable laterally to open and permit the coin to drop into a lower compartment 27 . Said bottom 26 is movable to drop a coin mounted thereon jointly by the crank rod 28 and the wedge member 29 . The crank rod 28 extends vertically and, as shown, is pivoted in brackets $28'$ and the bottom 26 comprises a laterally-extending arm at the lower end of said rod which moves pivotally on the rocking of said crank arm to release a coin mounted thereon. Said rod is provided at the upper end with an arm $28'$ which extends into the path of movement of the slide 6 so that upon the insertion of each successive coin, the rod will be rocked and the preceding coin will be dropped into the compartment 27 . The wedge member 29 is connected to the pivoted manually-operable spring-closed bottom 30 which upon inward movement by the fingers will cause the wedge surface $29'$ to engage and move the bottom 26 to cause any coin on the movable bottom 26 to be dropped into the hand of the operator. The movement of the bottom 30 also enables the operator to empty coins in that compartment into his hand. The rod 28 also has an intermediate arm 28^a which is engaged by a spring 28^c fastened at 28^d to normally retain the bottom in closed position and to keep the arm $28'$ in contact with the slide 6 .

In Figs. 7 to 18 I have shown a modified form of fare box in which the diameter-gauging coin-actuated lever mechanism, and the coin-gripping mechanism are all substantially similar to that hereinabove described, the principal difference in construction being that the countershaft 7 is provided with a ratchet wheel 31 and the end of the primary lever 5 is connected with pawl 32 (see Fig. 10) guided into engagement with the wheel 31 by guides $32'$. The movement and functions of the levers 5 and 12 in this construction and of the latching and other mechanism connected therewith are similar to that hereinabove particularly described though the springs and other parts are positioned and shaped somewhat differently. Another difference in construction is that the main latch member comprises an arm 33 extending directly across from the primary lever 5 to a pin on the auxiliary lever 12 . Still another difference in construction is the employment of a coin-separating element 34 and separate chutes 35 and 36 for the nickel and dime respectively.

In Figs. 7 to 9, 13, 13a and 13b I have shown two forms of coin-gripping mechanism to prevent retraction of inserted coins. Figs. 13a and 13b show my preferred form of coin gripping mechanism which effectively prevents retraction of a coin as soon as a section thereof is inserted in the coin slot. In this form the gripping-contact elements 16^b , 17^b are inclined downwardly from the pivots $16'$, $17'$ and provide a secure grip on the coin C as indicated in Fig. 13b. The inclination of the elements 16^b , 17^b downwardly from the fixed mounting pivots causes a stronger wedging action than when these elements are substantially horizontal as shown in Figs. 7 to 9 and 13.

In other essential respects the mechanism is similar to that hereinabove described.

Having described my invention, I claim:

1. In a fare register of the character specified, a casing having a coin-insertion slot, a counter-mechanism having character wheels and an actuating shaft, a pair of pivoted levers having coin-contact portions arranged at opposed ends

and partially obstructing said coin-slot against the admission of coins of varying diameters, one of said levers having a counter-actuating connection with said actuating shaft and a range of movement sufficient to produce plural or single registering movements of the counter-actuating shaft, said lever being movable by coins of varying diameters, and the other lever cooperating with said counter-actuating lever and having a coin-contacting portion spaced from the coin-contacting portion of said counter-actuating lever a distance in stationary position sufficient to cause a coin of relatively short diameter to move the coin-contacting part of said counter-actuating lever to produce a plural registering movement of said counter-actuating shaft, latching means for retaining said cooperating lever in stationary position during insertion of a coin of relatively short diameter and releasable to cause movement thereof by a coin of relatively long diameter whereby said counter-actuating lever and said actuating shaft will be moved through a lesser distance to produce a single registering movement.

2. In a fare register of the character specified, a casing having a coin-insertion slot, a counter-mechanism having character wheels and an actuating shaft, a pair of pivoted levers having coin-contact portions arranged at opposed ends and partially obstructing said coin-slot against the admission of coins of varying diameters, one of said levers having a counter-actuating connection with said actuating shaft and a range of movement sufficient to produce plural or single registering movements of the counter-actuating shaft, said lever being movable by coins of varying diameters, and the other lever cooperating with said counter-actuating lever and having a coin-contacting portion spaced from the coin-contacting portion of said counter-actuating lever a distance in stationary position sufficient to cause a coin of relatively short diameter to move the coin-contacting part of said counter-actuating lever to produce a plural registering movement of said counter-actuating shaft, latching means for retaining said cooperating lever in stationary position during insertion of a coin of relatively short diameter and releasable to cause movement thereof by a coin of relatively long diameter whereby said counter-actuating lever and said actuating shaft will be moved through a lesser distance to produce a single registering movement; said contact portions of said levers being so spaced that a coin of intermediate diameter will act to release said latching mechanism and move both levers but will move said counter-actuating lever a distance less than required to cause a registering movement.

3. In a fare register of the character specified, a casing having a coin-insertion slot, a counter-mechanism having character wheels and an actuating shaft, and coin-actuated lever mechanism comprising a primary pivoted, spring-pressed counter-actuating lever connected at one end with said counter-actuating shaft and having its other end yieldingly obstructing one end of the coin slot and having a range of movement sufficient to produce plural or single registering movements of said shaft, and an auxiliary pivoted, spring-pressed lever yieldingly obstructing the opposite end of said slot and movable in the opposite direction a distance sufficient to compensate in movement for the difference in diameter of a larger coin over a smaller one, latching mechanism connected with said

auxiliary lever for retaining said auxiliary lever in stationary position during insertion of a coin of relatively short diameter to cause a movement of said primary lever sufficient to produce a plural-registering movement thereof, said latching mechanism being releasable by a coin of relatively long diameter and the power of the springs pressing said levers being relatively arranged to cause initial movement of said auxiliary lever and a subsequent movement of said primary lever to produce a single-registering movement of said shaft.

4. A fare register embodying, in combination, a casing having a coin insertion slot, a counter-mechanism mounted in said casing having character wheels and an actuating shaft adapted upon a relatively short rotary movement to move its character wheels to count one and upon a greater movement of said shaft to move its character wheels to count two, and coin-actuated lever mechanism comprising a primary spring-pressed counter-actuating lever connected at one end with said counter-actuating shaft and having its other end yieldingly obstructing one end of the coin slot and an auxiliary compensating lever releasable and movable by a coin of relatively large diameter to free insertion space and to limit movement of the counter-actuating lever by a large diameter coin, said compensating auxiliary lever being provided with a part obstructing the other end of said coin slot at a predetermined position and having a main latch member unlatchable only through movement of the primary counter-actuating lever and also provided with a secondary latch member also obstructing said end of the coin slot at a position spaced from said primary lever a distance greater than the length of the diameter of a coin of relatively short diameter, said auxiliary lever in latched position being engageable with one edge of a shorter diameter coin to force the other edge against the primary lever to produce a long movement with a double count on said counter, said primary lever and secondary latch being simultaneously engageable by a longer diameter coin to unlatch both latches and permit an initial diameter-compensating and space-freeing movement of said auxiliary lever, and a stop member positioned to limit the compensating movement of said auxiliary lever by one edge of a coin of relatively long diameter to force the opposite edge of said coin on insertion to move the primary lever to a position producing a single-count on the counter mechanism.

5. A fare register embodying, in combination, a casing having a coin insertion slot, a counter-mechanism mounted in said casing having character wheels and an actuating shaft adapted upon a relatively short rotary movement to move its character wheels to count one and upon a greater movement of said shaft to move its character wheels to count two, and coin-actuated lever mechanism comprising a primary spring-pressed counter-actuating lever connected at one end with said counter-actuating shaft and having its other end yieldingly obstructing one end of the coin slot and an auxiliary compensating lever releasable and movable by a coin of relatively large diameter to free insertion space and to limit movement of the counter-actuating lever by a large diameter coin, said compensating auxiliary lever being provided with a part obstructing the other end of said coin slot at a predetermined position and having a main latch member unlatchable only through movement of

the primary counter-actuating lever and also provided with a secondary latch member also obstructing said end of the coin slot at a position spaced from said primary lever a distance greater than the length of the diameter of a coin of relatively short diameter, said auxiliary lever in latched position being engageable with one edge of a shorter diameter coin to force the other edge against the primary lever to produce a long movement with a double count on said counter, said primary lever and said secondary latch being simultaneously engageable by a longer diameter coin to unlatch both latches and permit an ini-

tial diameter-compensating and space-freeing movement of said auxiliary lever, and a stop member positioned to limit the compensating movement of said auxiliary lever by one edge of a coin of relatively long diameter to force the opposite edge of said coin on insertion to move the primary lever to a position producing a single-count on the counter mechanism, the distance between said stop-limited position of said auxiliary lever and the single-count producing position of said primary lever being greater than the diameter of an intermediate sized coin.

SOREN MADSEN.
